UNITED STATES PATENT OFFICE.

JACOB SPITZER, OF NEW YORK, N. Y., ASSIGNOR TO UNIVERSAL MERCERIZING & DYEING CO., INC., A CORPORATION OF NEW YORK.

MERCERIZING-MACHINE.

1,374,118.

Specification of Letters Patent.

Patented Apr. 5, 1921.

Application filed February 12, 1920. Serial No. 358,025.

To all whom it may concern:

Be it known that I, JACOB SPITZER, a citizen of Hungary, having declared my intentions to become a citizen of the United States, and a resident of the city of New York, borough of Manhattan, in the county and State of New York, have invented a new and improved Mercerizing-Machine, of which the following is a full, clear, and 10 exact description.

The invention relates to apparatus for mercerizing cotton yarn by the use of caustic soda or similar mercerizing solutions.

The object of the invention is to provide 15 a new and improved mercerizing machine arranged to effectively and economically mercerize a large amount of yarn at each operation and in a comparatively short time.

Another object is to provide a mercerizing 20 machine which is continuous and automatic in operation and does not require the services of highly skilled labor.

Another object is to insure an effective 25 penetration of the mercerizing solution into the fibers of the yarns to produce an even coiling action of the fibers and to firmly set the fibers, while in stretched condition, thus insuring the production of the desired sheen and without undue shrinkage of the yarn.

Another object is to provide a mercerizing 30 machine which is not liable to get easily out of order.

With these and other objects in view, the 35 invention consists of certain novel features of construction, as hereinafter shown and described and then specifically pointed out in the claims.

A practical embodiment of the invention 40 is represented in the accompanying drawings forming a part of this specification, in which similar characters of reference indicate corresponding parts in all the views.

Figure 1 is a side elevation of the improved 45 mercerizing machine;

Fig. 2 is a plan view of the same;

Fig. 3 is a sectional side elevation of the 50 same on the line 3—3 of Fig. 2;

Fig. 4 is a cross section of the same on the 55 line 4—4 of Fig. 1;

Fig. 5 is a similar view of the same on the 60 line 5—5 of Fig. 1;

Fig. 6 is an elevation of the right hand 65 side of the improved mercerizing machine;

Fig. 7 is a reduced end elevation of the 70 solution tank, the solution pan and the washing pans;

Fig. 8 is an enlarged sectional side elevation of the mechanism for controlling the switch of the motor driving the feed screw for intermittently reciprocating the carriage 60 supporting one of the yarn drums;

Fig. 9 is a cross section of the reversing switch for the electric motor for driving the carriage feed screw;

Fig. 10 is a cross section of a portion of 65 the mounting of one of the pressing and squeezing rollers;

Fig. 11 is a reduced side elevation of the cam device for actuating the washing pan;

Fig. 12 is a reduced sectional side elevation 70 of the cam device for controlling the raising and lowering of the mercerizing solution pan or tank;

Fig. 13 is a reduced sectional side elevation 75 of the cam device for controlling the hot and cold water supply; and

Fig. 14 is a reduced sectional side elevation 80 of the cam device for controlling the squeezing roller.

The improved mercerizing machine is 85 mounted on a suitably constructed main frame 20 and is preferably of duplex construction to allow of simultaneously mercerizing two batches of cotton yarn on the opposite sides of the machine with an attendant 90 stationed at each side to place the batches of cotton yarn to be mercerized in position on the machine and to remove the mercerized batches from the machine, it being understood that the machine is wholly 95 automatic and continuous in operation and requires no attention on the part of the attendants except as above stated. On each side of the main frame 20 is arranged a pair of drums 21 and 22, and each pair of 100 drums is adapted to receive a separate batch of cotton yarn 23, each batch consisting of a plurality of hanks of cotton yarn arranged side by side and opened up to permit of slipping each batch of cotton yarn over the outer unsupported drum ends onto the corresponding pair of drums 21 and 22 at the time the drums of each pair are in position near each other, as hereinafter 105 more fully explained.

The drums 21 and 22 of each pair of drums are parallel and the two drums 21 are provided with a common shaft 24 journaled intermediate the inner ends of the drums 21 in bearings 25, attached to the main frame 110 20. The drums 22 have a shaft 26 in common, journaled in a carriage 27 mounted to

reciprocate intermittently on guideways 28 forming part of the main frame 20. The carriage 27 is provided with a nut 30 (see Figs. 2 and 3) in which screws a feed screw 31 journaled in a bearing 32 attached to or forming part of the main frame 20. On the outer end of the feed screw 31 is secured a gear wheel 35 in mesh with a pinion 36 (see Figs. 1, 3 and 6) mounted to rotate on a stud 37 attached to the main frame 20. On the pinion 36 is secured a gear wheel 38 in mesh with a pinion 39 secured on the shaft 40 of a motor 41, preferably of the electric type. The motor 41 is provided with a reversing switch 42 (see Fig. 9) to permit of running the motor intermittently in opposite directions, as hereinafter more fully described, and with a view to correspondingly turn the feed screw 31 by the gearing described to move the carriage 27 and its drum 22 toward or from the drum 21.

When the carriage 27 and the drums 22 are in innermost position then the batches of cotton yarn can be readily slipped by the attendants over the outer unsupported end of the drums 21, 22, and then the motor 41 is reversed and the carriage 27 is moved outward to draw the batches of cotton yarn taut, and finally to stretch the same at the time the carriage 27 reaches an outermost position. The motor 41 is then automatically stopped as hereinafter more fully explained, and immediately previous to the carriage 27 reaching an outermost position, the drums 21 are rotated to impart a traveling motion to the batches of cotton yarn. For this purpose the following arrangement is made: On the shaft 24 intermediate the bearings 25 are mounted to rotate loosely bevel gear wheels 50 and 51 in mesh with a pinion 52 secured on a shaft 53 journaled in a suitable bearing 54 attached to the main frame 20. On the shaft 53 is secured a gear wheel 55 in mesh with an intermediate gear wheel 56 mounted to rotate on a stud 57 attached to the main frame 20. The gear wheel 56 is in mesh with a gear wheel 58 secured on a worm shaft 59 journaled in suitable bearings 60 attached to the main frame. On the shaft 59 (see Fig. 3) is secured a worm wheel 65 in mesh with a worm 66 secured on the main driving shaft 67 journaled in suitable bearings 68 attached to the main frame 20. On the main driving shaft 67 are secured fast and loose pulleys 69 and 70 connected by belt with other machinery for imparting a rotary motion to the main driving shaft 67 with a view to rotate the shafts 59 and 53 by the gearing described. The rotary motion of the shaft 53 is transmitted by the pinion 52 to the gear wheels 50 and 51 to rotate the latter in opposite directions. The gear wheels 50 and 51 are provided at their opposite faces with clutch members 75 and 76 adapted to be engaged by clutch mem-

bers 77 and 78 of a double clutch 79 keyed or otherwise fastened to the drum shaft 24 (see Fig. 3). When the double clutch 79 is in neutral position, as shown in Fig. 2, then the rotary motion of the gear wheels 50 and 51 does not affect the drums 21, but when the double clutch 79 is shifted to engage the clutch member 77 with the clutch member 75 then the driven gear wheel 50 rotates the drums 21 in one direction, and when the double clutch 79 is shifted to engage the clutch member 78 with the clutch member 76 then the gear wheel 51 turns the drums 21 in an opposite direction.

The double clutch 79 is automatically shifted from neutral into either of the three positions above mentioned with a view to intermittently rotate the drums, first in one direction and then in an opposite direction. For this purpose the following arrangement is made: The double clutch 79 is engaged by the upper forked end of a shifting lever 85 fulcrumed at 86 on the main frame 20, and on the lower end of the said shifting lever 85 is mounted a friction roller 87 engaging a cam groove 88 on the peripheral face of a cam 89 (see Fig. 4) secured on a transversely extending shaft 90 journaled in suitable bearings 91 arranged on the main frame 20. On the shaft 90 is secured a worm wheel 92 in mesh with a worm 93 secured on the shaft 59 previously mentioned and driven from the main shaft 67. When the machine is running the rotary motion of the shaft 59 is transmitted by the worm 93 and worm wheel 92 to the shaft 90 whereby the cam 89 is rotated and swinging motion is periodically given to the shifting lever 85 to move the double clutch 79 from neutral position successively into engagement with the gear wheels 50 and 51 to rotate the drums 21, first in one direction and then in the opposite direction, after which the double clutch 79 is returned to its neutral position. The drums 21 then come to a stop.

The drums 21 begin to rotate immediately previous to the carriage 27 moving into outermost position so that a traveling motion is given to the yarns at the time the drums 22 draw the yarns taut and into stretched condition. The lower runs of the two batches of traveling yarns pass through potash, soda or other mercerizing solutions contained in pans or open tanks 100 adapted to move up and down. The mechanism for moving the two pans 100 simultaneously up and down is the same and it suffices to describe but one in detail. Each of the pans 100 is provided with depending tubes 101 (see Figs. 1, 3, 5, 6 and 7) mounted to slide up and down on rods 102 attached to the main frame 20. On the tubes 101 is mounted to slide up and down a crosshead 103, the upward movement of which is limited by stop collars 104 adjustably secured on the 130

sleeves 101. Each crosshead 103 is provided with a grooved roller 106 engaged at the under side by one end of a lever 107 mounted to swing loosely on a transverse pivot rod 108 attached to the main frame 20. The lever 107 is provided with a suitable counterbalance 109 and on the lever 107 is journaled a friction roller 110 engaging the peripheral face of a cam 111 secured on the driven shaft 90, previously mentioned. The pans 100 are normally in lowermost positions but immediately after the yarns begin to travel, the cams 111 impart an upward swinging motion to the levers 107 whereby an upward sliding movement is given to the pans 100 to encompass the bottoms of the drums 21, 22 and the lower runs of the batches of yarn 23 to cause said lower runs to travel through the mercerizing solution contained in the pans 100, during the time the batches of yarn are under tension. During the time the yarn takes up the mercerizing solution the yarn is subjected to pressure in order to cause the solution to permeate thoroughly the fibers of the yarn. For this purpose use is made of pressing or squeezing rollers 120, one for each drum 21, and journaled in arms 121 mounted to swing loosely on a rock shaft 122 as a pivot, the rock shaft being journaled in the main frame 20. On the rock shaft 122 is keyed or otherwise secured an arm 123 (see Fig. 10) provided with a bolt 124 engaging a segmental slot 125 formed in the corresponding arm 121 to permit of adjusting the pressing or squeezing roller 120 on the rock shaft 122. By reference to Fig. 1, it will be noticed that the yarn passes between the drum 21 and the pressing or squeezing roller 120 and consequently is pressed or squeezed to saturate the yarn with the mercerizing solution and to press surplus mercerizing solution out of the yarn. On the rock shaft 122 is secured a depending arm 130 (see Figs. 4 and 14) and on the lower end of this arm 130 is journaled a friction roller 131 engaging the peripheral face of a cam 132 secured on the main shaft 90. By the arrangement described the pressing or squeezing rollers 120 are periodically pressed in firm contact onto the yarn at the drums 21.

After treating the batches of yarn with the mercerizing solution the yarn is washed with hot water and then with cold water, and for this purpose the following arrangement is made: A transverse spraying pipe 140 is located above the top runs of the two batches of yarn 23, and a similar transverse spraying pipe 141 extends transversely between the upper and lower runs of the two batches of yarns, and the said spraying pipes 140 and 141 are connected with a vertical pipe 142 terminating at its lower end 65 in a horizontal pipe 143 connected with a transverse pipe 144 connected at its ends with a cold water supply valve 145 and a hot water supply valve 146, the valves 145 and 146 being connected by pipes 147 and 148 with corresponding cold and hot water supplies under pressure. The valve stems 150 and 151 of the valves 145 and 146 are connected by links 152 and 153 with levers 154 and 155 mounted to swing on the pivot rod 108 as the fulcrum. The levers 154 and 155 are provided with friction rollers 156 and 157 engaging the peripheral faces of cams 158 and 159 secured on the cam shaft 90. The cams 158 and 159 are so arranged that the hot water valve 146 is first opened 75 for a given time to pass hot water to the spraying pipes 140 and 141 with a view to subject the batches of yarn to a washing action of hot water. The valve 145 is next opened to allow cold water to pass to the spraying pipes 140 and 141 to subject the batches of yarn to the washing action of cold water. The valve stems 150 and 151 are pressed on by springs 160 and 161 to normally hold the valves in a closed position and to quickly close the said valves as soon as the cams 158 and 159 drop off the corresponding rollers 156 and 157. It is understood that prior to passing washing water to the spraying pipes 140 and 141 85 the pans 100 have moved into lowermost position and water receiving pans 170 are moved into position under the drums 21, 22 above the lowered pans 100 to prevent the washing water from passing into the pans 100. The water receiving pans 170 are normally located on the right hand end of the machine and the said pans 170 are provided with wheels 171 mounted to travel on longitudinally extending guideways or rails 172 90 attached to suitable standards or posts 173. The right hand ends of the water receiving pans 170 are provided with depending arms 175 (see Figs. 1, 5, 6 and 7) having transverse pins 176 engaging the forked and slotted upper ends 177 of arms 178 secured on a transverse rock shaft 179 journaled in suitable bearings 180 attached to the right hand end of the main frame 20. On the rock shaft 179 is secured an arm 181 provided with a slot in which is adjustably secured a pivot 183 on a link 184 pivotally connected with a lever 185 (see Figs. 1 and 11) 105 fulcrumed at 186 on the main frame 20. The lever 185 is provided with a friction roller 187 in contact with the peripheral face of a cam 188 secured on the cam shaft 90 so that when the machine is running, the cam 188 imparts periodically a swinging movement to the lever 185. A spring 189 is attached at one end to the main frame 20 and at the other end to the arm 181 to swing the arms 178 from their normal outermost position, shown in dotted lines in Fig. 1, 110 into innermost position, shown in full lines 130

in Fig. 1, to move the water receiving pans 170 from their normal outermost positions inward into position below the drums 21 and 22 and the lower runs of the batches 5 of cotton yarn 23, mounted on the drums, at a time. It will be noticed that when the water receiving pans 170 are in this position the valves 146 and 145 are successively 10 opened to subject the batches of yarn to washing actions and while the yarns are traveling and pressed on by the spraying or squeezing rollers 120. The water flows into the pans 170 thus preventing such wash water from passing into the solution pans 100. After the valves 146 and 145 are 15 closed, the cam 188 acts on the lever 185 whereby the link 184 and arm 181 are actuated to rock the shaft 179 and thus cause the arms 178 to move the water receiving 20 pans 170 back into outermost position at the right hand end of the machine. Each water receiving pan 170 is provided with a water discharge spout 190 located outside the right hand ends of the solution pans 100 25 to allow of discharging the wash water without danger of it passing into the pans 100.

The starting, stopping and reversing of the motor 41 is automatically controlled by 30 actuating the reversing switch 42 from the cam shaft 90 to move the carriage 27 and with it the drums 22 in proper sequence relative to the other devices controlled from the cam shaft 90. For the purpose mentioned 35 the following arrangement is made, special reference being had to Figs. 1, 2, 8 and 9: The reversing switch 42 is of usual construction and its transverse rock shaft 200 is provided at one end with an arm 201 terminating at its free end in a pin 202 engaging a timer cam 203 secured on the cam shaft 90. The cam 203 is provided with a rim 204 adapted to be engaged by the pin 202, and the said rim is provided with a cut-out portion 205 adjacent to which is arranged a lug 206 on the web of the cam 203. The other end of the switch shaft 200 is provided with an upwardly extending arm 210 having an apertured head 211 through which extends 40 the threaded end 212 of a rod 213 pivotally connected with a bracket 214 attached to the carriage 27 to cause the rod 213 to move with the carriage. On the threaded end 212 of the rod 213 are slidably mounted collars 215, 45 216 adapted to engage the opposite sides of the head 211 of the arm 210. The collars 215 and 216 are pressed on by springs 217 and 218 abutting against collars 219, 220 abutting against nuts 221, 222 screwing on 50 the threaded end 212 of the rod 213. By the arrangement described, the springs 217 and 218 are alternately compressed during the movement of the carriage 27 from the right to the left or from the left to the right. 55 Against the nuts 221 and 222 abut trip arms

225 and 226 secured in place by nuts 227 and 228 screwing on the threaded end 212 of the rod 213. The trip arms 225 and 226 are adapted to engage screw rods 230 and 231 70 adjustably mounted in angular arms 232 and 233 of catches 234 and 235 pivoted at 236 and 237 on the main frame 20 on opposite sides of the arm 210. The catches 234 and 235 extend through an opening 238 formed in the arm 210, and the said catches are 75 adapted to engage the opposite sides of the head 211 to lock the arm 210 periodically against movement, as hereinafter more fully explained. The catches 234 and 235 are pressed on by springs 239 and 240 to move 80 the said catches upward into locking engagement with the opposite sides of the head 211. The screw rods 230 and 231 are adjustably mounted in the angular arms 232 and 233 by screwing therein, and lock nuts 85 242 and 243 are used for locking the screw rods 230 and 231 in position after the desired adjustment is made.

Presuming that the machine is running and the several parts are in the position 90 shown in Fig. 8 with the carriage 27 moving from the right to the left and the cam 203 turning in the direction of the arrow shown in Fig. 8. It will be noticed that the spring 218 is compressed during this movement of the carriage 27 owing to the arm 210 being locked in place by the catch 235 with the collar 216 abutting against the right hand side of the head 211 of the arm 210. When the carriage 27 nears the ends 100 of its inward stroke to the left then the trip arm 226 engages the screw rod 231 thus imparting a swinging motion to the arm 233 whereby the catch 235 is disengaged from the head 211 at the time the pin 202 of the 105 arm 201 is at the beginning of the cut-out portion 205. The compressed spring 218 now imparts a swinging motion to the arm 210 whereby the switch shaft 200 is turned to move the switch into neutral position thus 110 stopping the motor. It will be noticed that the arm 210 is limited by the pin 202 striking the cam lug 206 thus holding the switch shaft 200 and consequently the switch in neutral position until the pin 202 drops off 115 the lug 206, and a further swinging movement is given to the arm 210 by the action of the spring 218. When this takes place the switch is moved into reversing position and consequently the motor is reversed to 120 move the carriage 27 from innermost to outermost position, that is, from the left to the right. When the arm 210 moves into its extreme position to the left, the catch 234 engages the right hand face of the head 211 125 thus locking the arm 210 and consequently the switch shaft 200 in position. When the arm 210 is in this locked position its left hand face is in engagement with the collar 215, and during the return movement of the 130

carriage 27 the rod 218 and collar 219 compress the spring 217, and when the carriage 27 nears the end of its return stroke then the tripping arm 225 engages the screw rod 230 thus imparting a swinging movement to the angular arm 232 to disengage the catch 234 from the head 211 of the arm 210 to unlock the latter. When this takes place the spring 217 imparts a swinging motion to the arm 210 from the left to the right whereby a rocking movement is given to the switch shaft 200 to return the switch to neutral position at the same time the shaft 200 imparts a downward swinging movement to the arm 201 whereby the pin 202 passes through the cut-out portion 205 to engage the pin with the peripheral face of the rim 204. When the arm 210 moves to the right, the catch 235 reengages the left hand face of the head 211 thus again locking the arm 210 in the position shown in Fig. 8.

In order to keep the pans or tanks 100 charged with a mercerizing solution of uniform strength, the following arrangement is made, special reference being had to Figs. 5, 6 and 7. Each of the pans 100 is provided with a supply pipe 250 which extends into the pan through the bottom to within a short distance from the top, as plainly indicated in Fig. 6, at the right hand side thereof. The supply pipe 250 is approximately of U-shape and is slidably engaged at its free end by a pipe 251 connected with an overhead tank 252 adapted to contain a mercerizing solution. Each of the tanks 100 is provided with an overflow pipe 253 slidably engaging a pipe 254 discharging into a collecting tank 255 arranged to one side of the machine. A pump 256 of any approved construction has its suction pipe 257 extending into the collecting tank 255, and the discharge pipe 258 of this pump discharges into the overhead tank 252. Thus by the arrangement described the mercerizing solution in the overhead tank 252 can flow by way of the pipes 251, 250 into the pans 100 to keep the same supplied with a mercerizing solution maintained at a uniform level by the overflow pipes 253 through which the mercerizing solution passes to the collecting tank 255 to be returned by the pump 256 to the overhead tank 252. Thus by the arrangement described, the mercerizing solution is kept in circulation and its strength can be uniformly maintained to insure proper mercerizing of the cotton yarn. It is understood that a sliding connection of the pipes 250 and 253 with the pipes 251 and 254 is necessary owing to the up and down movement of the pans 100.

The operation is as follows:

When the machine is running and the carriage 27 and its drums 22 are in innermost position, that is, with the drums 22 nearest the other drums 21, then the attendants on

both sides of the machine place the batches of yarn 23 onto the said drums by way of the outer unsupported ends thereof. It is understood that for the time being the carriage 27 is at a standstill to give the attendants ample time for first removing the previously mercerized batches and to replace the same by new batches of yarn to be next mercerized. When this has been done, the cam 203 nears the position shown in Fig. 8 70 and the tripping arm 226 engages the screw rod 231 to unlock the arm 210 and allow the switch 42 to start the motor 41 whereby the feed screw 31 is turned and the carriage 27 is moved into outermost position. During this movement of the carriage the yarn is gradually drawn taut and is finally stretched a predetermined amount, and when this has been reached the switch 42 is moved into neutral position by the action of the cam 203 and the mechanism connected with the arm 210. The motor 41 now ceases to run and the carriage 27 is held in outermost position for the time being. Immediately previous to the carriage 27 coming to a stop, 90 that is, prior to the finishing of the stretching of the yarn 23 the double clutch 79 is shifted in one direction to impart a rotary motion to the drums 21 whereby the yarn 23 begins to travel to insure an even, final 95 stretching of the yarn throughout the length thereof. At this stage of the operation, the water receiving pans 170 are in outermost positions and the pans 100 containing the mercerizing solution are now raised to encompass the bottom portions of the drums 21, 22 and the lower runs of the yarns 23 whereby the said lower runs are immersed in the mercerizing solution and travel through the same. By the arrangement described the 100 yarn takes up the mercerizing solution and this operation is continued for say three minutes, but about a quarter of a minute earlier the squeezing rollers 120 are swung from their inactive positions into active positions against the yarn 23 at the drums 21, 105 as shown in Fig. 1. The pressing or squeezing rollers 120 force the mercerizing solution thoroughly into the yarn to insure a thorough incorporation of the solution in the 110 fibers of the yarn. The rotary movement of the drums 21 is reversed about every minute by the action of the cam 89 on the shifting lever 85 manipulating the double clutch 79 to cause the lower runs of the yarns to travel 115 alternately in opposite directions through the mercerizing solution in the tanks 100. By this action an even coiling of the ends of the fibers of the yarns is produced.

At the end of the three minutes referred 120 to the solution pans 100 are lowered by the corresponding action of the cam 111, as previously explained, and during this downward movement the pressing or squeezing rollers 120 remain in contact with the yarns 130

to squeeze out the surplus mercerizing solution, which drops down into the corresponding solution pans 100. The pressing or squeezing rollers 120 then move back into inactive position and at the same time the water receiving pans 170 are moved from their outermost positions into innermost position, that is, under the drums 21, 22 and the yarns 23 and over the solution pans 100, 10 as indicated in Fig. 1. The hot water valve 146 is now opened by the action of the corresponding cam 159 to allow hot water to pass into the spraying pipes 140 and 141 thereby delivering hot water onto the yarns 15 23 to wash off the caustic soda or other mercerizing material used. It is understood that the spraying pipe 140 delivers hot water to the outside of the yarns while the pipe 141 delivers hot water to the inside of 20 the yarns thus insuring a thorough washing of the yarn with hot water. This washing operation is continued say for one minute and then the hot water valve 146 is closed and the cold water valve 145 is opened 25 to deliver cold water by the spraying pipes 140 and 141 to the traveling batches of yarn 23, and this washing process is continued for another minute. As soon as the washing with hot and cold water begins, the 30 pressing or squeezing rollers 120 are returned to active position to squeeze out the water, but the rollers 120 return to inactive position during the last half minute of washing with cold water so that some of 35 the cold water remains in the yarn and is not squeezed out of the same. It is understood that the water squeezed out of the yarn during the time that the pressing or squeezing roller 120 is active passes into 40 the water receiving pans 170 to discharge the water through the outlet spout 190 to a suitable place of discharge. After the washing operation is completed and the valve 145 is again closed then the water 45 receiving pans 170 return to outermost position and the motor 41 is now again started by the action of the cam 203 and the mechanism connected with the arm 210 whereby the carriage 27 is moved from its outermost 50 position back into innermost position to gradually release the tension of the yarn 23 and to allow the same to become slack. When the innermost position of the carriage is reached the attendants remove the batches 55 of mercerized yarns from the drums 21 and 22 and the above described operation is then repeated, it being understood that about half a minute is needed for removing the batches of mercerized yarn and to replace 60 the same by other batches to be next mercerized. It is understood that the timer cam 203 is arranged to hold the switch 42 in neutral position for about five minutes, and during this time the mercerizing and 65 washing operations are carried on. The

carriage 27 when in innermost position is stopped for about a half minute to allow of taking off the mercerized yarn and putting on the new batch to be mercerized. Thus the entire operation consumes about 70 six minutes and as the machine is running continually it is evident that a large amount of yarn is mercerized in a comparatively short time.

Having thus described my invention, I 75 claim as new and desire to secure by Letters Patent:—

1. In a mercerizing machine a pair of drums adapted to support a batch of cotton yarn to be mercerized, a carriage carrying 80 one drum to move the latter toward and from the other drum, a reversing motor connected with the said carriage to intermittently reciprocate the same, starting and stopping means for the said motor and including a timer cam and mechanism controlled by the said carriage, and driving means for one of the said drums to impart a traveling motion to the yarn, the said driving means turning the said timer cam. 90

2. In a mercerizing machine, a pair of drums adapted to support a batch of cotton yarn, an intermittently traveling carriage carrying one of the drums, a motor having a reversing switch, a feed screw driven from 95 the said motor and engaging the said carriage to intermittently reciprocate the carriage, a revoluble timer cam, and a mechanism connected with the said switch, the said carriage and the said timer cam to control the said switch. 100

3. In a mercerizing machine, a pair of drums adapted to support a batch of cotton yarn, an intermittently traveling carriage carrying one of the drums, a motor having 105 a reversing switch, a feed screw driven from the said motor and engaging the said carriage to intermittently reciprocate the carriage, a revoluble timer cam and a mechanism connected with the said switch, the 110 said carriage and the said timer cam to control the said switch, means for driving the other drum to impart a traveling motion to the yarn, a pan adapted to contain a mercerizing solution and adapted to move up 115 and down to engage and disengage the traveling yarn with the said mercerizing solution, washing means to subsequently wash the yarn, pressing and squeezing means to press and squeeze the yarn while being subjected to the action of the mercerizing solution and while being washed, and a main driving means for rotating the said drum and including a cam shaft carrying the said timer cam and cams for controlling the 120 washing water supply, the pressing and squeezing roller and the up and down movement of the said pan. 125

JACOB SPITZER,
